UNITED STATES PATENT OFFICE

2,462,101

ELEVATED TANK

George T. Horton, Chicago, Ill., assignor to Chicago Bridge & Iron Company, a corporation of Illinois

Application September 28, 1944, Serial No. 556,153

7 Claims. (Cl. 220—1)

1

This invention relates to improvements in elevated tanks and more especially an elevated steel tank such as is commonly used for storage of water and other liquids. The invention is particularly applicable to tanks of large storage capacity, for example from 2,000,000 to 5,000,000 gallons or larger.

In elevated water tanks of large capacity such as used for a municipal water supply and the like, it is necessary or desirable to maintain a certain minimum head in order to supply the desired pressure. One of the features of my invention is to provide a structure of large capacity in which the variation of head from full capacity to empty will be small. In other words, in large tanks of this kind it is desirable to obtain the increased capacity by additional horizontal area of the tank rather than by additional height. By increasing the capacity, excess pressures are avoided and consequently saving in cost is effected.

Another feature of my invention is the provision of a tank of the character described that can be easily and economically built. It is also a relatively simple matter to adapt my tank to various shapes of ground upon which the tank is to be erected. It is also relatively simple to design a tank embodying the features of my invention for any desired capacity.

In DeVore Patent 2,346,129 a structure is shown in which the bottom of an elevated tank comprises a plurality of intersecting inverted truncated cones. This structure achieves most of the foregoing objects but is somewhat unsightly. The device shown herein is readily constructed and the side walls serve to conceal the multitude of cones so that the structure of the tank may be integrated more readily with any suitable outline or design.

The invention is illustrated in the drawings in which Fig. 1 is a top plan view; Fig 2 is a view in side elevation; Fig. 3 is a fragmentary top plan view with the roof removed; Fig. 4 is a view taken as indicated by the line 4—4 of Fig. 3; Fig. 5 is a detailed perspective, showing the roof supporting members; Fig. 6 is a view taken as indicated by the line 6—6 in Figure 1; Fig. 7 is a top plan view taken as indicated by the line 7—7 in Figure 6; Fig 8 is a top plan view taken as indicated by the line 8—8 in Figure 4; and Fig. 9 is a fragmentary sectional view illustrating a modified form of the invention.

As shown in the drawings, the tank 9 comprises primarily a bottom formed of a plurality of upright intersecting conical frustums or truncated cones 10, 10, supported by tubular columns

2

or posts 11, 11. These cones may be circular, generally circular, or polygonal. It is preferred, if they are circular, that the shape thereof be deformed downwardly at the intersections so that the lines of intersection 10a shall be horizontal, and that all of the intersections will lie in a horizontal plane. In this way interdrainage of the cones is provided at all portions except a negligible portion of the non-intersecting area of the outermost ring of cones. Drainage from the depressed areas of the cone may be provided by an inverted conical frustum 10b centrally located in the tank. It may also be provided in any other way, not shown, as for example, drainage members from each of the bottom portions to one or more of the vertical posts. The tubular columns or posts may each be a drain or may serve as a riser pipe but preferably the tops of all but one or more are closed by plates 11a. Preferably the central pipe 11b which supports an inverted conical frustum 10c is left open to serve as a riser pipe. At intervals vertical channels 13 may be provided on the plates 11a to support the horizontal channels 14 which in turn carry straps 15 adapted to support the roof 16.

In Figure 7 the line 17 represents the line of intersection of two of the cones. This line when viewed from the top or from the side is preferably straight, the cone being deformed adjacent thereto to accomplish this result. If the cones are permitted to intersect on their normal lines of curvature, line 17 would be curved upwardly and would leave undrained pockets on each line of intersection.

The tank may be made in substantially any shape desired, as viewed from the top. As here shown, it is hexagonal and comprises 37 intersecting conical frustums, of which 36 are upright and one is inverted. The cones in the outer row 40 as here shown have their side faces closed by diaphragms 18. The inner faces are partially closed by the triangular diaphragms 51 and 52, the triangular space indicated by 53 being left open. 54, 54 indicate stiffening members on the diaphragms.

The outer shape of the structure may of course be modified as viewed from the side. For example, while I have shown a structure which is substantially rectangular, as viewed from the side, this 50 may be rounded at the corners to provide a curved roof which merges the upper corners into the side walls, and curved side walls which merge at the bottom into a curved bottom which may or may not join the central riser pipe 11b at its apex. 55 The structure may comprise a single cone sur-

rounded by one or more rows of intersecting cones. Similarly the outer walls may comprise a series of circular segments, as viewed in a horizontal plane, or the outer walls may be merged into one continuous curve.

In Figure 9 I have shown a form of the tank in which the cones 100 are of the so called pagoda form in which the slope of the cone increases upwardly in a substantially hyperbolic form. Similarly, the inverted cone 100c is provided with a wall of decreasing slope in a downward direction which is reversed at the point of intersection to join the riser pipe 101.

The tanks herein described have a further advantage over the DeVore structure already referred to in that the metal within the upright cones is under tension, rather than compression, as is the case with an inverted cone.

The foregoing detailed description has been given for clearness of understanding only, and no unnecessary limitations should be understood therefrom.

What I claim as new, and desire to secure by Letters Patent, is:

1. An elevated steel tank having a bottom comprising a central inverted truncated cone supported by a riser pipe at its truncated vertex, a plurality of upright cones intersecting with said inverted cone and with each other to form the bottom of the tank, side walls connected to the outer cones, and a roof connecting the side walls.

2. An elevated tank having its bottom formed substantially entirely of a plurality of truncated cones, said cones being at least partially distorted so as to intersect at their bases and said cones being supported on posts which contact the cones at the truncated vertices.

3. A tank as set forth in claim 2 in which the bottom includes a central inverted truncated cone supported by a post at its vertex.

4. A tank as set forth in claim 2 in which substantially all of said intersections lie in a substantially horizontal plane.

5. An elevated metal tank comprising a bottom formed substantially of a plurality of upright

truncated cones intersecting at their bases, said cones being partially distorted so as to intersect in lines substantially all of which lie in a substantially horizontal plane, a roof member common to all the cones, a supporting post extending downwardly from each of the truncated vertices, a side wall extending between the roof and the bottom comprising a plurality of intersecting cylindrical segments arranged symmetrically around the vertical axis of the tank and each having a center of curvature substantially in the projected axis of one of said truncated cones and vertical diaphragms above the lines of intersection of truncated cones adjacent the side walls interconnecting said cones and said side wall segments.

6. A tank as set forth in claim 5 in which the bottom includes an inverted truncated cone extending below said plane of intersection and having a hollow riser pipe at its vertex.

7. An elevated metal tank comprising a bottom formed of a plurality of upright truncated cones, said cones being distorted at their bases to intersect in a substantially common plane, a roof member common to all the cones, a supporting post extending downwardly from each of the truncated vertices, a side wall extending between the roof and bottom comprising a plurality of intersecting cylindrical segments arranged symmetrically around the vertical axis of the tank, each having a center of curvature substantially in the projected axis of one of said truncated cones.

GEORGE T. HORTON.
